UNITED STATES PATENT OFFICE.

EDWARD E. STOUT, OF INDIANAPOLIS, INDIANA.

SHOE CUSHION.

Application filed June 7, 1923. Serial No. 643,825.

To all whom it may concern:

Be it known that I, EDWARD E. STOUT, a citizen of the United States, residing at Indianapolis, in the county of Marion and 5 State of Indiana, have invented a new and useful Shoe Cushion, of which the following is a specification.

It is the object of my invention to produce a shoe having a cushioning in-sole, whether 10 over the whole or a part of the sole, which avoids any objectionable creeping and wadding of the cushioning material; which creeping or wadding is probably caused by the pushing action of the foot in its back-and-forth action in the shoe, and especially 15 at the ball of the foot.

With ordinary cushioning material, such as felt, there is a pronounced tendency to make a hollow in ordinary cushioning material, especially at the ball of the foot, by pushing the cushioning material forward towards the toe of the shoe; which makes a very uncomfortable wadding of such cushioning material, and may result in serious 25 injury to the foot.

According to my present invention, I provide a cushioning material in which this action does not take place. For this purpose, I use a cushioning material which is 30 made up of fibers with the upper end of each fiber anchored in definite position in a suitable membrane, and the lower end preferably free. This membrane which anchors the upper end of the fibers is thus toward 35 the foot, with or without any other interposed layer such as a sock-lining, so that the upper ends of such fibers are positively held from being pushed out of place. The most 40 convenient material I have found for this is a natural material—"lamb's-wool" (including wool from either sheep or lamb)—which I use with the woolly side down and the skin or flesh side up; but while I prefer this material my invention in its broader 45 aspect is not limited thereto.

The accompanying drawing illustrates my invention: Fig. 1 is a vertical longitudinal section through a shoe having an insole embodying my invention, with the cushioning in-sole extending the whole length of the shoe; Fig. 2 is a perspective view of the insole shown in Fig. 1, viewed obliquely upward from the bottom; and Fig. 3 is a view 50 similar to Fig. 1, but with the cushions only at the heel and the toe, and with a hard shank.

My in-sole is arranged to be used in the usual manner on the inside of a shoe, and to rest on the shoe-sole 10. This in-sole 11 includes a layer of cushioning material, as 60 shown in Figs. 1 and 2, and may be made as a piece of natural "lamb's wool", from either sheep or lamb, cut to the proper size and shape, and placed in the shoe with the woolly side 12 down toward the shoe sole 65 10, and the flesh side or skin 13 upward toward the foot. The skin 13 may itself serve as a sock lining, if desired, thus avoiding the necessity for any additional sock-lining layer; but it is not essential that there be 70 no other sock-lining put over the skin 13, if that is wished because of a desire for a different texture on the sock-engaging surface from that which the skin 13 provides.

By this "lamb's-wool" in-sole the cushion 75 is effectively prevented from creeping and wadding. The cushion is made up of a myriad of hairs; and the upper end of each hair is firmly anchored in the skin 13. In consequence, any back-and-forth movement 80 of the foot in the shoe, even at the ball of the foot, cannot greatly displace the upper ends of these fine hairs; and in use the hairs remain substantially in their original 85 position in the shoe regardless of any tendency of the foot to displace them.

While I prefer to use lamb's-wool as the cushioning material because of its softness and the great feeling of comfort which it gives to the foot, my invention is not limited 90 to this particular natural material as the cushion. I may use other furs, with the hair or wool side down and the flesh side or skin side up. In addition, I may use artificially prepared material, of any sort, where there is a great number of capillary fibers 95 each of which is anchored at one end in a membrane, as the wool of the lamb is anchored in the skin of the lamb. My invention in its broader aspect includes any such 100 material so placed in the shoe that the upper ends of the fibers are anchored in place.

It is not necessary that the cushioning material extend over the whole sole. The cushioning material may be located only at 105 the front end of the sole, below the ball of the foot and the toes; or only at the heel; or only at the two ends of the sole, front and rear, with no cushioning at the shank, as shown in Fig. 3. This arrangement with a relatively hard arch-supporting shank 110 and a cushioning material both in front of

and behind such hard shank is specifically set forth in my co-pending application, Ser. No. 643,824, of even filing date herewith; and my present invention is applicable to 5 that arrangement as well as to the structure where the cushioning material extends the whole length of the sole.

I claim as my invention:

1. In combination, a shoe having a sole, 10 and a shoe cushion upon said sole, said shoe cushion comprising lamb's-wool with the wool side down and the skin side up.
2. In combination, a shoe sole, and a lamb's-wool cushion thereon with the wool 15 downward and the skin upward.
3. In combination, a shoe having a sole,

and a shoe cushion upon said sole, said shoe cushion comprising a natural fur having the skin side up and the fur side down.

4. In combination, a shoe having a sole, 20 and a shoe cushion upon said sole, said shoe cushion comprising a multitude of capillary fibers, the lower ends of said fibers being free for relative motion, and a membrane in which the upper ends of said fibers are 25 anchored.

In witness whereof, I have hereunto set my hand at Indianapolis, Indiana, this 7th day of May, A. D. one thousand nine hundred and twenty three.

EDWARD E. STOUT.
